UNITED STATES PATENT OFFICE

FRANCIS C. SCHUBERT, OF SYRACUSE, KANSAS

DENTAL FLOSS HOLDER

Application filed March 5, 1929. Serial No. 344,468.

This invention relates to an improved dental floss holder especially made to permit the floss to be stretched tightly thereon in a manner to permit it to be conveniently drawn back and forth in a saw-like manner between the teeth.

Briefly described, the invention comprises a bottle like container for the dental floss, a cap on the container, a floss clamp on the cap, 10 a spring bow extending beyond the cap, and means on the bow, whereby the free end portion of the dental floss may be connected therewith, whereby to stretch a portion of the floss tightly between the bow and the clamp to permit it to be held in this taut manner to be conveniently drawn back and forth between the teeth for cleaning purposes.

A feature of the invention consists in the utilization of a bottle container which has 20 the additional function of a handle for manipulating the device.

A further feature is in having the top operating as a carrier for the spring bow, clamp and bottle embracing means associated with 25 said bottle.

Other features and advantages will become more readily apparent from the following description and drawings.

In the drawings:

30 Figure 1 is a perspective view of the complete appliance, showing the same substantially of full size.

Figure 2 is an enlarged fragmentary sectional view, showing the manner in which 35 the clamping means functions to bind the inner end portion of the floss.

Figure 3 is a horizontal sectional view on the plane of the line 3—3 of Figure 2.

Referring now to the drawings by reference 40 characters, it will be seen that the reference character 4 designates a small cylindrical glass bottle whose upper end is externally screw threaded for reception of a screw cap 5. The screw cap is formed with an opening 45 at the front for passage of the loose end portion 6 of the dental floss 7. The floss is wound on a spool contained in the bottle. The reference character 8 designates a spring clip 50 which embraces the bottle and which has an arm 9 extending therefrom and bent laterally

as at 10 and terminating in a bevelled disc like extremity 11. The peripheral portion of this disc like element 11 is bevelled. Fas- 55 tened to the part 11 through the medium of a rivet or the like 12 is a similar bevelled clamp- ing disc 13. These two discs form a clamp between which a portion of the dental floss is wound and bound.

One peripheral notch 14 is formed in the disc 13 on one side, just above the hole in 60 the cap 5. Thus, the free end portion 6 is drawn outwardly through the hole in the cap and one turn is made between the two discs 11 and 13 and then the cord is drawn outwardly through the notch 14 to provide 65 a cleaning stretch 15. The extremity of the cord 6 is fastened to an especially bent re- 70 silient keeper 17 on the bent extremity of the right angularly bent end portion 19 of the spring bow 20. This bow is fastened in an eye 21 on the arm 9 and firmly riveted at 22 on the clip 8 as shown in Figure 1. The bow is sufficiently resilient to maintain the stretch 15 of the cord under tension.

In practice, the free end portion of the 75 dental floss or cord is drawn outwardly through the opening in the cap and is wound between the two discs 11 and 13 where it is bound by a clamping action. It is then car- 80 ried upwardly through the notch 14 and wrapped around and connected with the keeper 17. Thus the portion 15 is stretched taut- 85 ly but resiliently so that it may be drawn in a saw like manner back and forth between the teeth for cleaning purposes. In this man- 90 nner, the bottle 4 acts as a handle for easy ma- nipulation. When this portion 15 has been cut off.

The arrangement is such that the end portion 19 and keeper 17 are directly over the notch 14 and the opening in the cap.

A careful consideration of the description 95 in conjunction with the drawings will enable the reader to obtain a clear understanding of the construction, features and method of ma- nipulation. Therefore, a more lengthy de- 100 scription is regarded as unnecessary.

Minor changes in the shape, size, and rearrangement of details coming within the field of invention claimed may be resorted to, in actual practice, if desired.

I claim:

5. 1. A dental floss holder comprising a container for the dental floss, a clip embracing the container and terminating in a clamping portion positioned above the mouth of the bottle, a disc secured to said clamping portion and cooperating therewith to present a circular groove of V-shaped cross section in which a portion of the dental floss is wound, a resilient bow carried by said clip and having an angularly bent portion extending over and spaced above the said clamping portion of the said clip, said angularly bent portion being adapted to have the extremity of the dental floss attached thereto and being flexed 15 to spring outwardly from the clamping portion of the said clip to cause the dental floss to become bound within the said groove.
10. 2. A dental floss holder comprising a dental floss containing member, a pair of clamping discs mounted on said container and presenting wedge-shaped clamping surfaces between which a portion of the dental floss is adapted to be engaged, a resilient bow mounted on the container and extending upwardly 20 thereof and terminating in a keeper to which the end of the dental floss is adapted to be connected, said keeper being tensioned to exert a pull on the dental floss to cause the latter to become clamped between the wedge surfaces of the clamping disc, and means for mounting said resilient bow on the said container.
15. 3. In a dental floss appliance of the class described, a dental floss containing bottle, a screw cap mounted on said bottle, a clip embracing the bottle and having an arm portion extending therefrom and terminating in a bevelled disc like portion, said disc-like portion being fastened to said cap, a second disc fastened to said disc-like portion and forming a clamp with the first mentioned disc between which a portion of the dental floss is adapted to be engaged, a resilient bow carried by said clip and arm and extending upwardly 25 beyond said cap, and having its upper extremities bent at right angles and terminating in a dental floss keeper to which the end of the dental floss is adapted to be connected for effecting tension on the floss, to cause the dental floss to become bound between the opposed surfaces of the said clamping discs.

In testimony whereof I affix my signature.

FRANCIS C. SCHUBERT.
